UNITED STATES PATENT OFFICE.

BATEMAN DAVID SCOTT, OF STRETFORD, MANCHESTER, AND WILLIAM HENRY TATE,
OF SALE, ENGLAND.

INTERNAL-COMBUSTION ENGINE.

1,295,803.

Specification of Letters Patent. Patented Feb. 25, 1919.

Application filed November 13, 1918. Serial No. 262,319.

To all whom it may concern:

Be it known that we, BATEMAN DAVID SCOTT, of 53 Moreton avenue, Stretford, Manchester, in the county of Lancaster, 5 England, and WILLIAM HENRY TATE, of 7 Westbourne Grove, Sale, in the county of Chester, subjects of the King of Great Britain and Ireland, have invented certain 10 new and useful Improvements in Internal Combustion Engines, of which the following is a specification.

This invention relates to internal combustion engines of the sleeve valve and four stroke cycle type.

15 Our invention comprises the combination with a single sleeve around the piston adapted to control at least two ports or sets of ports arranged at the opposite ends of the cylinder, one port or set of ports serving as 20 the inlet and the other for exhaust, of a fuel sprayer or injector adapted to spray the fuel directly into the engine cylinder, the air inlet port or ports being so positioned that no air is admitted to the cylinder until the 25 piston approaches the end of the suction stroke.

Referring to the accompanying explanatory drawing, the piston *a* works within a sleeve *b* which is reciprocated by suitable 30 means, such as the crank *c* and controls ports *d*, *e* in the cylinder *f*. The port *e* serves as the engine exhaust port and the port *d* as the air inlet port, the amount of air admitted 35 through the said port being regulated by the rotary throttle valve *g*.

The fuel is admitted to the cylinder through the injector or sprayer *h* which is capable of very fine adjustment and is opened mechanically at the required periods. 40 Or, it may open automatically against the pressure of its spring during the suction stroke. The use of an injector or sprayer enables us to work the engine on heavy fuels and to obtain complete atomization and vaporization of the charge prior to combustion.

The ports *i*, *j* in the sleeve *b* and the ports *d*, *e* in the cylinder are so positioned with 45 relation to one another and to the movement of the sleeve and piston, that the exhaust port is uncovered just prior to the completion of the power stroke of the piston and remains open throughout the exhaust stroke. The continued movement of the piston re-

sults in the production of a vacuous condition in the cylinder during the period in 55 which fuel is entering through the injector *h* until the port *d* is uncovered, when there is a strong inrush of air which results in a complete diffusion of the fuel throughout the charge ready for ignition and combustion. 60

Instead of employing a single port for the exhaust and for the inlet, we may employ a set of ports disposed around the cylinder.

Owing to the large area which may be 65 given to the exhaust and inlet ports and to the lightness of the valve mechanism with our improved construction, the engine is particularly suitable for high speed work.

By arranging the exhaust and the inlet 70 ports at the opposite ends of the single sleeve, as shown, lubrication of the bearing surface between sleeve and cylinder is effected by the oil vapor drawn from the crank case by the engine suction, and distributed during working. No oil gains access to the cylinder at the upper end of the sleeve and so a dirty exhaust and heavy deposits in the cylinder and exhaust fittings, 75 are prevented.

We do not limit ourselves to any particular means for actuating the sleeve *b* nor to the number or disposition of the cylinders constituting the engine. The latter may be 80 air or water cooled according to requirements.

Having now described our invention what we claim as new and desire to secure by Letters Patent is:—

1. In internal combustion engines of the 90 four cycle type, the combination with the engine piston and cylinder, of a valve sleeve around the piston and between the latter and the cylinder, air inlet and exhaust ports at the opposite ends of the cylinder, ports in 95 the said sleeve, means for operating the sleeve to control the cylinder ports and a fuel sprayer in the cylinder head for delivering fuel into said cylinder during the suction stroke and before the air inlet port is 100 opened.

2. In internal combustion engines of the 105 four cycle type, the combination with the engine piston and cylinder, of a valve sleeve around the piston and between the latter and the cylinder, an exhaust port adjacent the

cylinder head, an air inlet port adjacent the crank case end of the cylinder, ports in the said sleeve for registering with the cylinder ports, means for operating the sleeve to control the cylinder ports, and a fuel sprayer in the cylinder head for delivering fuel into said cylinder during the suction stroke, of

the engine and before the air inlet port is opened.

In testimony whereof we have signed our names to this specification.

BATEMAN DAVID SCOTT.
WILLIAM HENRY TATE.
